ATTORNEY

UNITED STATES PATENT OFFICE.

EDWARD HARTER, OF CHICAGO, ILLINOIS.

TELEPHONE ATTACHMENT.

1,291,499.

Specification of Letters Patent. Patented Jan. 14, 1919.

Application filed June 27, 1917. Serial No. 177,374.

To all whom it may concern:

Be it known that I, EDWARD HARTER, a citizen of the United States, residing at Chicago, in the county of Cook and State of Illinois, have invented certain new and useful Improvements in Telephone Attachments, of which the following is a specification.

This invention relates to a directory and particularly to a useful, convenient and ever-ready directory for a telephone which is designed to be applied to the transmitter near the base where it can be referred to at once when the number of the subscriber is wanted and which will be out of the way when using the instrument.

The object of the invention is to provide a directory for telephones which can be furnished cheaply and serve as advertising means for various business concerns, the directory being readily applied to the bottom of a telephone stand and, lying adjacent the base thereof, is out of the way when using the telephone, is in easy reach when a number is to be found, and which may be readily renewed whenever desired.

Another object of the invention is to provide a telephone directory, the support for which is cut from sheet metal and pressed into shape for attachment to a telephone transmitter, and provided with means for holding a plurality of indexed sheets of paper properly ruled and divided into columns for the names of subscribers alphabetically arranged, their various exchanges, and their telephone number.

With the above as the principal objects in view, the invention consists in the novel construction, combination, and arrangement of parts hereinafter described, pointed out in the appended claim and illustrated in the accompanying drawing, in which,

Figure 1 is an elevation of a telephone transmitter with the improved index in position thereon,

Fig. 2 is a top plan view of the supporting plate for the indexed sheet secured to the telephone transmitter standard, the latter being shown in cross section on the lines 2-2 of Fig. 1;

Fig. 3 is a perspective view of the indexed sheet supporting plate removed from the telephone stand.

Fig. 4 is a view of one of the indexed sheets.

In the drawing, A indicates a telephone

transmitter such as is in common use at the present day, *a* being the standard and *b* the base. Mounted upon the standard *a* just above the base *b* at one side of the standard *a* is a supporting plate or table 10 made preferably of sheet metal and rectangular or square in outline, the greatest dimension of the plate being preferably slightly less than the diameter of the base *b*. At one edge of the plate 10 are two arms 11 and 12 integral with the plate and each twisted upon itself at 13 to lie flatwise against the telephone standard *a*, the arms being curved at 14 to embrace the standard *a* and at their extremities, these arms are bent to lie substantially parallel as shown at 15 and perforated at 16 for a bolt 17 that extends through the hole 16 and by means of a nut 18 on said bolt, the arms are caused to grip the telephone standard *a* and hold the plate in any position desired in the length of the standard. The most convenient and suitable place, however, for the plate 10 is at the bottom of the standard *a*; the arms 11 and 12 being clamped to said standard where it joins the base *b*, a slight bend being given the two arms where they join the plate 10 so that said plate will lie at an angle or inclination to the support on which the transmitter is placed, thereby bringing the upper surface of said plate and the indexed sheets 20 thereon in convenient position to have their contents read.

The plate 10 forms a support for a plurality of indexed sheets 20 which may be of paper, celluloid or other material suitable for the purpose and each having an indexed tab 21 upon which is placed the first letter of the surname of such names as are written or printed upon the sheets 20. At the top of each sheet 20 near the corners are two perforations 22 by means of which the sheets 20 are secured to the plate 10. For this purpose, said plate has two tongues punched from the upper edge on each side of the arms 11 and 12 and bent upwardly and rearwardly to form two curved hooks 23 which open rearwardly and sufficiently above the top of the plate 10 to permit a bunch of sheets 20 sufficient for ordinary purposes to be threaded on the hooks and also removed therefrom when desired. The perforations 22 are sufficiently large to permit the sheets to be swung upwardly with perfect freedom so as to rest against the standard *a* when it is desired to refer to an under sheet. The tab 21 on each sheet 20 is offset from the

sheet above and below in the usual manner so that the letters on all the tabs are visible and preferably each sheet is provided with horizontal rulings 24 and divided into columns by spaced lines 25 and 26, thus dividing each sheet into spaces for name of the subscriber, the exchange and the number of the telephone, as indicated by the headings in Fig. 4.

10 To lessen the cost of manufacture so that these directories may be given away to the telephone subscribers, it is designed to print on the opposite back of each sheet 10 an advertisement which will be displayed whenever 15 the sheets are turned up in order to expose names on the sheet below. The face of each sheet may also have an advertisement at the bottom and a cover sheet (not shown) overlying the sheets 20 may also be used for 20 advertising purposes, both inside and outside being employed.

In using this directory after mounting the plate 10 upon the transmitter A and placing the sheets 20 in position on the plate 10, 25 such names as a subscriber refers to more or less often are written upon the sheets 20 under the proper index letter as, for instance, "Adams" would be written, as shown in Fig. 4, on the sheet with the "A" tab 21.

followed by the exchange in the proper column, and in the last column the telephone number would be written down; "Smith" would be found on the sheet with the "S" tab, and "Williams" on the sheet with the "W" tab, each with its proper exchange and telephone number.

I claim:

A support for writing sheets comprising a rectangular plate of sheet metal, a pair of arms integral with said plate projecting from one edge thereof and curved in opposite directions to closely embrace the standard of a transmitter, the terminal ends of said arms being bent in parallel relation, a thumb screw connecting said terminal ends and adapted to bind the arm to the transmitter standard, and a pair of rearwardly turned hooks at the upper edge of the supporting plate and integral therewith for holding a pack of writing sheets upon the plate.

In testimony whereof I affix my signature in presence of two witnesses.

EDWARD HARTER.
